Herbert G. Odell

ATTORNEY

UNITED STATES PATENT OFFICE.

FRED M. SLATER, OF EASTON, PENNSYLVANIA, ASSIGNOR TO INGERSOLL-RAND COMPANY, OF JERSEY CITY, NEW JERSEY, A CORPORATION OF NEW JERSEY.

IMPULSE-ACTUATED ROCK DRILL.

Application filed July 20, 1921. Serial No. 486,228.

To all whom it may concern:

Be it known that I, FRED M. SLATER, a citizen of the United States, a resident of Easton, county of Northampton, and State 5 of Pennsylvania, have invented a certain Impulse-Actuated Rock Drill, of which the following is a specification accompanied by drawings.

This invention relates to a fluid pressure 10 rock drill of the hammer type, in which the hammer piston may be actuated forwardly by intermittent impulses of motive fluid pressure admitted to and exhausted from the cylinder rearwardly of the piston.

15 In my copending application, Serial No. 486,227, filed July 20, 1921, I have disclosed a fluid pressure impulse system having an interrupter forming a part of the fluid supply for generating and controlling the fluid 20 impulses for operating a rock drill or other machine and one of the objects of the present invention is to enable a rock drill of the type disclosed in that application to be operated by means of impulses generated and 25 controlled by a device mounted upon and forming a part of the machine itself, so that the apparatus is unitary and self contained and may be connected to the system disclosed in said copending application or may 30 be connected to any usual supply line without the interposition of any special piece apparatus between the source of supply and the rock drill.

Further objects of the invention are to 35 improve upon machines, especially rock drills of the impulse type, economize motive fluid pressure and increase the efficiency of the machine.

To all of these ends the invention consists 40 of the machine shown in the accompanying drawings in one of its preferred forms, in which—

Figure 1 is a longitudinal sectional side view of a rock drill.

45 Figure 2 is a similar view with the piston at the forward end of its stroke, and

Figure 3 is a similar view partly broken away with the piston at the rearward end of its stroke.

50 Referring to the drawings, the cylinder A is formed with a main bore B, and a guiding bore C of reduced diameter is preferably formed within the front cylinder bushing D. A piston E is provided with a main head

F, reciprocating in the main cylinder bore 55 B, and a reduced shank G guided in the bore C.

The shank H of the hollow drill steel J extends within the chuck K, in the front head L, in position to receive the blows of 60 impact of the fluted end O of the hammer, 65 slideable in the chuck K but in non-rotatable engagement therewith. Rotation may be imparted to the piston and drill steel by means of the usual rifle bar P, having the ratchet Q in the back head R, to which the handle S is connected.

A distribution port T is located at the rear end of the cylinder A, and a casing U, which may be separate from the cylinder A 70 or an integral part of the cylinder, as shown, contains a device which may be in the form of a pressure actuated valve V, for controlling the impulse of fluid pressure for actuating the piston forwardly. In this instance, the fluid impulses are both admitted through and exhausted from the same distribution port T for convenience, and the main supply line W through which air un- 75 A controlling valve head d is connected to the casing U at the admission port X. The exhaust from behind the piston takes place through the exhaust port Y, from which it may be led back to the intake of the compressor. 80

85 The interrupter or valve V, is provided with an enlarged head Z operating in the chamber a closed by the plug b and in communication with the forward end of the main cylinder bore through the passage c. 90 A controlling valve head d is connected to the shank e by the stem f. When the admission port X in the casing U is opened to motive fluid pressure, the valve V will assume the position indicated in Figure 1, and an 95 impulse of motive fluid will be admitted to the cylinder rearwardly of the main piston head F. The immediate closing of the valve V in a manner to be disclosed, interrupts or cuts off the supply of fluid pressure to the 100 cylinder and the reciprocation of the valve V in the valve chest U controls fluid pressure impulses for operating the piston in a forward direction.

105 A passage g, leading from the rearward to the forward position of the cylinder, permits a portion of a fluid impulse, which actuates the piston forwardly, to pass to the

forward end of the cylinder and through the ports *h* to a volume chamber *j*. A valve *k* within the cap *o*, having a spring *p* tending to close the valve, traps that portion of the motive fluid which passes to the front end of the cylinder and to the volume chamber *j*, so that pressure in front of the main piston head *F* and expansion of the motive fluid serves as the sole means for returning the piston on its rearward stroke when the pressure behind the piston is exhausted through port *Y*. The pressure in front of the piston head *F*, communicated to the head *Z* of the controlling valve *V* through the passage *c*, moves said valve to the position indicated in Figure 2, as the piston reaches the end of its forward stroke, opening the exhaust from behind the piston through the port *Y*, which may be connected to the intake of the compressor and relieving the pressure behind the piston head on the return stroke. It is obvious that the exhaust *Y* may exhaust into the atmosphere, in which case the compressor will be obliged to draw in fresh air at each stroke.

Means are provided for exhausting the pressure from in front of the main piston head *F* when the piston reaches the end of its rearward travel, and I prefer to exhaust the fluid through the front end of the machine and through the hollow drill steel *J* for blowing out the drill hole. For this purpose, the reduced shank *G* of the piston is preferably provided with a beveled shoulder *q*, which arrives opposite the preferably beveled end *r* of the bore *C* in the bushing *D* when the piston reaches the end of its rearward travel, so that the fluid may be exhausted through the bore *C* and the fluted shank *O* of the piston, to the front end of the machine and thence through the drill steel.

In the operation of the machine, let it be assumed that the piston is traveling on its forward stroke and is in the position indicated in Figure 1, at which point the passage *g*, leading to the forward end of the cylinder is uncovered by the piston head *F*. An impulse of motive fluid has been admitted through the rear distribution port *T* of the cylinder, and is acting upon the larger pressure area of the main head *F* of the piston. The interrupter valve *V* is in the position indicated, and the exhaust *Y* is closed. As the piston reaches the end of its forward stroke, as indicated in Figure 2, the valve *V* is thrown into its opposite position cutting off the supply and opening the exhaust *Y* to the rear end of the cylinder. The expansion of the motive fluid in front of the main piston head *F* returns the piston on its rearward stroke to the position indicated in Figure 3, at which point the forward end of the cylinder is exhausted, as described, and the valve *V* is again

thrown to the position indicated in Figure 1, admitting another impulse of motive fluid to the cylinder and the cycle is repeated.

I claim:

1. An impulse actuated fluid pressure rock drill of the hammer type, comprising a cylinder having a main bore, a piston having a head and a reduced shank, means for actuating the piston forward by impulses of motive fluid intermittently introduced rearwardly of said piston head, a forward volume chamber in the cylinder communicating with the forward end of the main bore, means for passing a portion of each impulse of motive fluid to the forward end of the cylinder and the volume chamber including means for trapping said portion of the motive fluid at the forward end of the cylinder serving as the sole means for returning the piston on its rearward stroke, and fluid actuated means in communication with a constant pressure supply mounted on the cylinder for controlling the said actuating impulses of motive fluid and for exhausting the cylinder rearwardly of the piston head for the return stroke of the piston.

2. An impulse actuated fluid pressure rock drill of the hammer type, comprising a cylinder having a main bore, a piston having a head and a reduced shank, means for actuating the piston forward by impulses of motive fluid intermittently introduced rearwardly of said piston head, a forward volume chamber in the cylinder communicating with the forward end of the main bore, means for passing a portion of each impulse of motive fluid to the forward end of the cylinder and the volume chamber including means for trapping said portion of the motive fluid at the forward end of the cylinder serving as the sole means for returning the piston on its rearward stroke, fluid actuated means in communication with a constant pressure supply mounted on the cylinder for controlling the said actuating impulses of motive fluid and for exhausting the cylinder rearwardly of the piston head for the return stroke of the piston, and means controlled by the piston for exhausting the fluid trapped in front of the piston head and in the volume chamber.

3. An impulse actuated fluid pressure rock drill of the hammer type, comprising a cylinder having a main bore and a guiding bore of reduced diameter, a piston having a head in the main bore and a reduced shank guided in the reduced bore, an interrupter in communication with a constant supply of pressure fluid mounted on the cylinder for intermittently controlling impulses of motive fluid and admitting and exhausting said impulses of motive fluid rearwardly of the piston head, a forward volume chamber

- in the cylinder separate from and independent of the cylinder bore and communicating with the forward end of the main bore, a passage for passing a portion of each impulse of motive fluid to the forward end of the cylinder and the volume chamber and a valve for closing said passage and trapping said portion of the motive fluid in the cylinder after the piston has travelled a portion of its forward stroke, the expansion of the fluid from the volume chamber serving as the sole means for actuating said piston rearwardly.
4. An impulse actuated fluid pressure rock drill of the hammer type comprising a cylinder having a main bore and a bore of reduced diameter, a piston reciprocating in the cylinder having a head in the main bore and a forwardly extending reduced shank guided in the bore of reduced diameter, a volume chamber in the forward end of the cylinder around the reduced bore but sepa-
- rate and independent therefrom and communicating with the main cylinder bore, said cylinder having a distribution port at the rear end of the main bore and a supply passage leading from the rear to the front of the main bore, a valve controlling said supply passage, a casing on the cylinder and an interrupter therein in communication with a constant supply of pressure fluid for controlling impulses of motive fluid from the supply through the said rear cylinder distribution port and for exhausting the main bore behind the piston head, the impulses of motive fluid behind the piston head driving the piston forward, and the expansion of fluid trapped in front of the piston head and in the volume chamber serving as the sole means for returning the piston on its rearward stroke.

In testimony whereof I have signed this specification.

FRED. M. SLATER.
